UNITED STATES PATENT OFFICE.

CALVIN L. ORSBORN, OF SELMA, ALABAMA.

SEED-COTTON-DISTRIBUTING VALVE MECHANISM.

1,249,469.

Specification of Letters Patent. Patented Dec. 11, 1917.

Application filed March 22, 1915. Serial No. 16,181.

To all whom it may concern:

Be it known that I, CALVIN L. ORSBORN, a citizen of the United States, residing at Selma, in the county of Dallas and State of Alabama, have invented certain new and useful Improvements in Seed-Cotton-Distributing Valve Mechanism, of which the following is a specification.

The present invention relates to improvements in seed cotton distributing valve mechanism.

In the ginning of cotton it is common to use two or more gins or two or more sets of gins. These gins are supplied with seed cotton by a suitable conveying mechanism which is preferably of a pneumatic character such as is illustrated in the present application. It is found convenient, in operating such gins, to accumulate in a suitable chamber, known as a vacuum chamber a charge of cotton in its unginmed condition, and then to feed that charge to the gins from one side to the other of the mechanism. In other words, if this machine was set in the center of six, eight or ten gins, it would alternately distribute a charge on the right and a charge on the left until the feed was exhausted. Further, while the machine feeds the charge to one side and then dumps, it distributes to all the vacuum chambers until the other side is near-closed. It distributes to all vacuum chambers at the same time, but it dumps to only one side at a time automatically.

To this end it is common to provide over each gin a vacuum chamber and to these vacuum chambers is connected an air duct common to all chambers.

It has been found difficult to properly regulate the filling of the vacuum chambers but this difficulty may be obviated by the use of such apparatus as is disclosed in the present invention.

The objects of this invention are, therefore,

First, the provision of a seed cotton distributing valve mechanism, which can be applied to the usual pneumatic elevator for cotton gins, and which will cause an even and uniform distribution of the seed cotton to the different vacuum boxes for the several gins;

Second, the provision of a seed cotton distributing valve mechanism, which will produce a proper feed of seed cotton and distribute the same equally among the vacuum

boxes of the several gins, and by proper control of such valve mechanism to effect the distribution of the seed cotton in such manner that a greater quantity of the seed cotton is fed in a given time to the vacuum boxes which communicate with the gins;

Third, the provision of a mechanism such as above referred to, which will give an alternate movement to the valves, said movement capable of shifting the entire feed of seed cotton from its source of supply to half of the number of gins, on one side of the device, and then to the other half of the number of gins on the opposite side;

Fourth, to provide means whereby, after two alternative movements of the valves that shift the entire feed of cotton from the wagon or supply house to one-half of the number of gins and then to the other half of such number, the valves will stand open for a time thereby equally dividing the entire feed of cotton to all of the vacuum boxes;

Fifth, to provide means, whereby upon the operation of a hand lever these valves will be thrown out of gear and permitted to stand open for any desirable length of time without stopping the operation of the mechanism, thus enabling a new supply of seed cotton to be immediately elevated and stored equally in all the vacuum chambers while the previous charges that have passed through the valves are being ginned out.

Sixth, to provide means whereby a hand lever can be operated that will control a valve located between the seed cotton distributing mechanism and the exhaust fan of the system, so as to cut off the suction from the vacuum boxes of the gins and permit the seed cotton to drop to the gins, after which this valve can be opened and thus permit the passage of the pneumatic suction of the exhaust fan to the vacuum boxes and a new supply of seed cotton to be immediately elevated and stored up in the vacuum boxes, while the cotton that was dropped to the gins by the closing of this valve, is being ginned out;

Seventh, to provide means whereby another valve will be opened when the valve that cuts off the entire pneumatic suction is closed, the positions of these two valves always being opposed so that when the pneumatic suction valve is closed, the other valve will open the suction pipe to the air and

serve as a ventilating port for the exhaust fan, thus enabling the fan to continue doing useful work, such as blowing seed, etc., when it has been cut off from the pneumatic system;

10 Eighth, the provision of a mechanism, such as above referred to, which will be comparatively simple and inexpensive to manufacture, reliable and efficient in use and readily operated, it being understood that various minor changes in the specific details of construction can be resorted to within the scope of the appended claims, without departing from the spirit or sacrificing any 15 of the advantages.

20 With the above and other objects in view, the present invention resides in the novel features of construction, formations, combinations and arrangements of parts, to be hereinafter more fully described, claimed and illustrated in the accompanying sheets of drawings, forming a part of this application, and in which:

25 Figure 1 is a side elevation of the invention with parts in section;

Fig. 2 is an end view thereof with parts in section and broken away;

Fig. 3 is an enlarged sectional view illustrating one of the gate valves;

30 Fig. 4 is a view illustrating a fragmentary and enlarged section of the operating mechanism of one of the gate valves and the means for throwing the same out of operative position;

35 Fig. 5 is a similar view showing the means for releasing the cross-head;

Fig. 6 is a horizontal sectional view taken on the line VI—VI of Fig. 2 on a reduced scale; and

40 Fig. 7 is an enlarged sectional view taken on line VII—VII of Fig. 2.

Fig. 8 is a transverse vertical section of a vacuum chamber or box used in connection with the invention.

45 Referring to the accompanying three sheets of drawings by similar characters of reference throughout the several views, the numeral 10 denotes in general, my improved mechanism, including the vacuum chambers 50 11 and air chambers or ducts 12 which extend from the opposite sides thereof and connect with the vacuum chambers 11. The vacuum chambers have communication with a cotton supply by means of the flue 13 while 55 the air chambers connect to a suction flue shown at 14 and lead through the extension 15, to a suction or exhaust fan, not shown.

The flues 11 and 12 are controlled by the gate valves 16—16 and 17—17 while the flue 60 14 is controlled by the gate valve 19, as shown in Figs. 1, 2 and 6.

The extension or suction flue 15 is provided with an enlarged portion 20, having a ventilating port 21 formed therein, which is 65 controlled by a valve 22. The valves 19 and

22 are arranged and connected in such manner, as indicated in Fig. 1, that when one is opened the other will be closed. To this end, a standard 23 is mounted upon the upper side of the flue 14 and has journaled in its 70 upper forked end 24 a sprocket wheel 25 over which a chain 26 is passed in engagement with the teeth of the said sprocket wheel. The opposite ends of this chain 26 are attached to the upper ends of the valves 75 19 and 22.

Guides 27 and 28 are provided for the valves 19 and 22 to operate in, while secured to the valve 19 is a bracket 29 to which is pivotally connected a vertically movable operating rod 30.

The lower end of this rod 30 is pivotally connected as at 31 to the upper free end of a T-shaped lever 32, the opposite end of which is pivoted as at 33 to a bracket 34 preferably attached to the under 85 side of the flue 13. The depending end 35 of the lever 32 is pivoted as at 36 to one end of an operating rod 37 having a handle 38 formed upon its opposite end. This lever has spaced sets of notches 39 and 40 pro-

90 vided in its lower edge for engagement with a locking device 41 provided with a tooth 41^a arranged to selectively engage in said notches. When the operating rod 37 is in the position shown in Fig. 1, with the locking device 41 in engagement with the notches 39, the valve 19 is in its open position and the valve 22 in its closed position which arrangement produces a suction throughout the entire system of flues. When, however, 100 the rod 37 is moved so that the teeth 40 are in engagement with the locking device 41, the valve 19 will be in its closed position, which shuts off the suction from the system of flues and the valve 22 opened which acts 105 as a seal for the flue 15 and permits the fan (not shown) to be used as a blower for any desired purpose such as blowing seeds to bins, cars, stock houses and the like, to any reasonable distance desired.

110 A suitable frame work 42 is mounted over the flues, and consists preferably of the uprights 43 connected at their lower ends to the flues and at their upper ends by the upper horizontal bars 44. Intermediate and lower 115 horizontal bars 46' and 46 are connected to the uprights 43.

120 Shafts 47, 48, 49 and 50 are journaled upon bars 46' intermediate of bars 46 and each of said shafts has keyed thereto intermeshing large and small gears 51 and 52 (see Fig. 1) which reduce the speed of the shafts from 47 to 50 respectively. A pulley 53 is keyed to the shaft 47 and has a belt 54 engaging the same which leads to any 125 suitable source of power, whereby a continuous rotary motion can be imparted to the shaft 47 and thence through the gears 51 and 52 to the shaft 50.

130 Guides 55 and 56 are mounted in the

frame work 42 and slidably receive and support the sliding blocks 57 and 58. These blocks 57 and 58 are reciprocated in opposite directions in the guides 55 and 56 by the connecting rods 59 and 60 which extend from the diametrically oppositely arranged crank arms 61 and 62 at the ends of the shaft 50 as shown in Fig. 2.

Trip rods 63 and 64, see Figs. 2, 4 and 5, 10 are secured to the blocks 57 and 58 and depend therefrom, terminating at their lower ends in shouldered heels 65 and 66 and outwardly slanting toes 67 and 68. These heels 65 and 66 are adapted to engage the upper 15 horizontal flanges 69 of the cross heads 70 and 71, which are connected to the vertical valve stems 72 and 73 of the valves 16 and 17, respectively, the connections being such as to permit free downward movement of 20 the cross heads with respect to the stems so that the valves close by gravity and at all times may properly seat. In order to effect such a connection each cross head is provided with spaced ears 71^a through 25 which the respective valve stems slide, such stems being each provided at this upper end with a collar 72^b held on the stem by a nut 72^c.

Upon the rotation of the shaft 50, the 30 blocks 57 and 58 will be alternately raised and lowered, which operation also raises and lowers the trip rods 63 and 64. As these rods 63 and 64 are lowered, the heels 65 and 66 will, under usual conditions, engage the 35 flanges 69 of the cross heads 70 and 71, thereby forcing the latter downwardly and permitting closing of the valves 16 and 17 in their proper order. When, however, the rods 63 and 64 respectively, reach the lower 40 limit of their movement the toes 67 and 68 will engage properly arranged lugs 68' supported in bars 46, and be forced outwardly, releasing the respective heel 65 or 66 from the flange 69 of the depressed cross head and 45 leaving that cross head 70 or 71 and valve 16 or 17 carried thereby free to move upwardly.

In order to provide for the upward movement of the cross heads 70 and 71 and 50 valves 16 and 17, chains 74 and 75 are attached to the cross heads 70 and 71 as shown at 76. These chains 74 and 75 pass over the pulleys 77 and 78 journaled on stub shafts 79 which extend from the bars 45. Weights 55 80 are attached to the lower ends of the chains 74 and 75 and are greater in weight than the weights of the cross heads 70 and 71 and valves 16 and 17, so that when the cross heads are released from the rods 63 60 and 64, the heads will be immediately returned to their raised positions and the respective valve 16 or 17 opened, the cross head being in position for reengagement by the respective rod 63 or 64.

65 In order that the rods 63 and 64 can be

moved to inoperative positions, so as not to effect the operating of the valves 16 and 17 upon the rotation of the shaft 50, longitudinal shafts 81 and 82 are supported on and journaled in the frame 42 and have oppositely disposed arms 83 and 84 keyed thereto, which are connected by a link 85 for the purpose of causing the rotation of the shaft 81 upon the rotation of the shaft 82. To provide for the rotation of these shafts 81 and 82, an arm 86 extends from the shaft 82 and has pivoted to its free end, as at 87, an operating rod 88 provided at its lower end with a handle 89 and provided adjacent the same with notches 90 for engagement with a locking device 91 by means of which the rod 88 can be locked in its upper or lower position. Pawls 92 and 93 are keyed to the shafts 81 and 82, respectively, and are disposed adjacent the paths of the bars 63 and 64 being 85 sufficiently close that rotation of the shafts 81 and 82 causes movement of the ends of these pawls into contact with the rods. Obviously, upon the rotation of the shafts 81 and 82 through the medium of the rod 88, the pawls 92 and 93 will be swung outwardly and force the lower ends of the rods 63 and 64 outwardly, so that the heels 65 and 66 will pass over the flanges 69 of the cross heads 70 and 71 without engaging the same and 95 permit the blocks 57 and 58 to be lowered without operating the valves 16 or 17, thus leaving all of said valves open as shown in Fig. 2.

In order to provide against leakage at the 100 points whereby any of the gate valves pass through the flues, packings 94 may be seated in recesses 95 provided in the upper sides of the said flues, as shown for example in Fig. 3. The packings are held in place by plates 105 96 which are held in engagement with the upper sides thereof by wing nuts 97. Similar packings 98 are seated in recesses 99 provided in the lower sides of the flues and are provided with V-shaped grooves 100 to engage the V-shaped edges of the gate valves.

In operation when the fan is started the valve 19 is normally open and the valve 22 closed. At the same time that the fan is started the mechanism operating the belt 54 115 is started. The gearing is so arranged that the charge in one vacuum chamber will be completely ginned during one-half revolution of the crank shaft 50, the belt being connected to the gin in any suitable manner, not 120 shown, to effect this purpose. The result of this will be that the valves 16 will be closed for a short period of time while the gin beneath the left hand vacuum chamber 11 is receiving its charge, see Fig. 6. Mean- 125 while the right hand vacuum chamber 11, will be in communication with the seed cotton supply flue 13 and the suction duct 15, the air chamber or duct 12 on the right hand communicating with the right hand vacuum 130

chamber 11 through a screen 11^a which is common to such devices and which is constructed and arranged as shown for example in Fig. 8, and operated as described and shown in my former U. S. Patent No. 1,051,439. When the right hand chamber 11 has become filled with its charge, the crank shaft will have revolved so as to close the valves 17, and thereby cut off such right hand chamber 11, so that its contents may fall into the gin on the right. Meantime, the empty left hand chamber 11, will have been placed in connection with the supply flue 13 and suction duct 15, as described in connection with the right hand duct 11, by the raising of the valves 16, so that its chamber 11, will now be filled. Thus the chambers 11, 11, will be alternately filled and emptied, as the valves 16 and 17 are alternately closed for a short time to permit the seed cotton to drop into the gins, and alternately opened for a longer period of time to elevate the seed cotton to be later discharged or dropped into the gins as just described.

From the foregoing it will be manifest that a seed cotton distributing valve mechanism is provided which will fulfil all of the necessary requirements of such a device.

30. What I claim is:

1. In a device of the kind described, a plurality of vacuum chambers adapted to receive seed cotton, suction means connected to said vacuum chambers, oppositely upwardly and downwardly moving valves arranged to alternately cut off said chambers from the vacuum means, means for operating said valves and manually controlled means arranged to engage and render the valve operating means ineffective.

2. The combination with a plurality of seed cotton receiving chambers, of upwardly and downwardly moving valves controlling said chambers, means for actuating the valves to a closed position, means for releasing the valves from the actuating means closing the valves, means for returning the valves to open position by action of gravity, a suction flue in communication with the seed cotton chambers, said suction flue having a vent port therein and means for alternately opening and closing the suction flue and vent port.

3. In an apparatus such as described, a plurality of cotton receiving chambers, a suction flue in communication therewith, upwardly and downwardly moving valves controlling the chambers, means engaging the valves for moving them downwardly to a closed position, means for releasing the valves, and means for automatically returning the valves to raised position.

4. In an apparatus such as described, a plurality of cotton receiving chambers, upwardly and downwardly moving valves con-

trolling the chambers, operating means for moving the valves downwardly to a closed position, means for releasing the valves from the operating means, means for automatically raising the valves after their release from the operating means, and means for disengaging and rendering the operating means inoperative.

5. An apparatus such as described, comprising oppositely disposed vacuum or cotton receiving chambers, a valve for controlling each of said cotton receiving chambers, a supply flue communicating with said vacuum or cotton receiving chambers, oppositely disposed air chambers adjacent to the vacuum or cotton receiving chambers, the air chamber on one side communicating with the cotton receiving or vacuum chamber on the same side, a valve for each of said air chambers controlling the communication between the air chamber and vacuum or cotton receiving chamber on the same side, and a suction flue communicating with the oppositely disposed air chambers between the valves controlling the communication between the air and vacuum or cotton receiving chambers.

6. An apparatus such as described, comprising oppositely disposed vacuum or cotton receiving chambers, a valve for controlling each of said cotton receiving chambers, a supply flue communicating with said vacuum or cotton receiving chambers between the valves controlling the vacuum or cotton receiving chambers, oppositely disposed air chambers adjacent to the vacuum or cotton receiving chambers, the air chamber on one side communicating with the cotton receiving or vacuum chamber on the same side, a valve for each of said air chambers controlling the communication between the air chamber and vacuum or cotton receiving chamber on the same side, a suction flue communicating with the oppositely disposed air chambers between the valves controlling the communication between the air and vacuum or cotton receiving chambers, and a valve in said suction flue controlling the exhaust or vacuum in the air chambers.

7. An apparatus such as described, comprising oppositely disposed vacuum or cotton receiving chambers, a valve for controlling each of said cotton receiving chambers, a supply flue communicating with said vacuum or cotton receiving chambers between the valves controlling the vacuum or cotton receiving chambers, oppositely disposed air chambers adjacent to the vacuum or cotton receiving chambers, the air chamber on one side communicating with the cotton receiving or vacuum chamber on the same side, a valve for each of said air chambers controlling the communication between the air chamber and vacuum or cotton receiving chamber on the same side, a suction flue

communicating with the oppositely disposed air chambers between the valves controlling the communication between the air and vacuum or cotton receiving chambers, and 5 means for alternately opening and closing the valves controlling the oppositely disposed air and vacuum or cotton receiving chambers.

8. An apparatus such as described, comprising oppositely disposed vacuum or cotton receiving chambers, a valve for controlling each of said cotton receiving chambers, a supply flue communicating with said vacuum or cotton receiving chambers between 10 the valves controlling the vacuum or cotton receiving chambers, oppositely disposed air chambers adjacent to the vacuum or cotton receiving chambers, the air chamber on one side communicating with the cotton receiving or vacuum chamber on the same side, a valve for each of said air chambers controlling the communication between the air chamber and vacuum or cotton receiving chamber on the same side, a suction flue 15 communicating with the oppositely disposed air chambers between the valves controlling the communication between the air and vacuum or cotton receiving chambers, means for alternately opening and closing the 20 valves controlling the oppositely disposed air and vacuum or cotton receiving chambers, and means for disengaging the valve actuating means and making the same inoperative.

35 9. In a device of the kind described, a plurality of vacuum chambers, suction means normally connected to said vacuum chambers, valves controlling the connections between said chambers and suction means, 40 means to alternately close said valves including a trip mechanism, and a manually controllable device for rendering the operation of the trip mechanism ineffective and thereby permitting all of said valves to remain open.

45 10. In an apparatus such as described, a plurality of seed cotton receiving chambers, valves controlling said chambers, a suction flue in communication with the seed cotton 50 chambers, said suction flue having a vent opening therein, valves controlling the suction flue and vent opening, an operative connection between the valves whereby they will alternately open and close the suction flue 55 and vent opening, an operating rod connected to one of said valves, and means for actuating the rod to operate said valves, and means for locking the valves against movement.

60 11. In an apparatus such as described, a plurality of oppositely extending cotton receiving chambers, valves controlling said chambers, valve stems connecting the valves of the oppositely extending chambers in series, a shaft, arms extending from the shaft,

a pair of guides, oppositely operating blocks 65 slidable in the guides, an operative connection between the blocks and arms, means for rotating the shaft, means carried by the blocks and engaging the cross heads for closing said valves, means for disengaging the means carried by the blocks from the cross heads, and means for returning the valves to raised position upon their release.

12. In an apparatus such as described, a plurality of oppositely extending cotton receiving chambers, valves controlling said chambers, cross heads converting the valves 70 controlling the oppositely extending chambers in series, guides disposed adjacent the 75 chambers, blocks slidable in the guides, means for sliding said blocks in opposite directions, operating bars carried by said blocks and having heels formed at the lower ends thereof for engaging the cross heads, 80 and outwardly slanting toes, whereby upon the downward movement of the blocks the valves will be moved to closed position, means disposed in the path of the toes for moving the bars outwardly and disengaging 85 the heels from the cross heads and releasing the valves, and means for raising said valves upon their release from the operating bars.

13. In an apparatus such as described, a plurality of cotton receiving chambers, a 90 frame disposed above said chambers, oppositely operating valves controlling the chambers, a shaft journaled in the frame, means for rotating the shaft, guides mounted in the frame, blocks slidably mounted in the 95 guides, an operative connection between the blocks and shaft for alternately operating the blocks, cross heads connecting the valves of each oppositely operating series, operating bars secured to the blocks and having 100 heels at their lower ends for engaging the cross heads and moving the valves to closed position, outwardly slanting toes extending from the heels, blocks disposed in the paths 105 of the toes for engaging the latter and moving the heels out of engagement from the cross heads, and means for returning the valves to raised position.

14. In an apparatus such as described, a frame, cotton receiving chambers extending 110 from the frame, valves controlling the chambers, cross heads connecting the valves in series, operating bars movable in the path of the cross heads for engagement therewith, means for actuating the bars, shafts journaled in the frame, means for rotating the shafts and pawls carried by the shafts and disposed in the paths of the bars for engagement therewith, whereby upon the rotation of the shafts, the pawls will force the 115 bars out of the path of the cross heads.

15. A seed cotton distributing apparatus comprising a plurality of seed cotton receiving chambers, a seed cotton feed suction flue normally in communication with the 120 125 130

seed cotton receiving chambers, a valve for each of said seed cotton receiving chambers controlling its communication with the seed cotton feed suction flue, a plurality of 5 vacuum chambers each one of which is in communication with its corresponding cotton receiving chamber, a suction flue normally in communication with said vacuum chambers, a valve for each of said vacuum chambers controlling its communication with the suction flue and means for operating the valves controlling the communication between receiving chambers and feed

suction flue and between the vacuum chambers and suction flue whereby all of the cotton receiving chambers are in communication with the cotton feed suction flue and all of the vacuum chambers are in communication with the suction flue. 15

In testimony whereof I affix my signature 20 in presence of two witnesses.

CALVIN L. ORSBORN. [L. s.]
